UNITED STATES PATENT OFFICE.

SAMUEL F. ELLIS, OF DES MOINES, IOWA.

DESIGN FOR A CIGARETTE-BOX AND ASH-TRAY.

No. 37,581.

Specification for Design.

Patented Oct. 24, 1905.

Application filed May 1, 1905. Serial No. 258,410. Term of patent 7 years.

To all whom it may concern:

Be it known that I, SAMUEL F. ELLIS, a citizen of the United States, residing at Des Moines, in the county of Polk and State of Iowa, have invented a new, original, and ornamental Design for Cigarette-Boxes and Ash-Trays, of which the following is a specification, reference being had to the accompanying drawing, forming part thereof.

The figure shows a perspective view of the

cigarette-holder and ash-tray, showing my new design.

I claim—

The ornamental design for a cigarette-box and ash-tray, as shown.

SAMUEL F. ELLIS.
